UNITED STATES PATENT OFFICE.

ALBERT M. WESTON, OF BOSTON, MASSACHUSETTS, ASSIGNOR TO EVERETT E. KENT,
OF NEWTON, MASSACHUSETTS.

SERVING DEVICE FOR EATING-HOUSES.

1,170,790.

Specification of Letters Patent. Patented Feb. 8, 1916.

Application filed June 3, 1909. Serial No. 499,985.

To all whom it may concern:

Be it known that I, ALBERT M. WESTON, a citizen of the United States, residing at Boston, in the county of Suffolk and State 5 of Massachusetts, have invented new and useful Improvements in Serving Devices for Eating-Houses, of which the following is a specification.

This invention relates to serving devices 10 for eating-houses.

The invention provides means by which the patrons of such a house are served in a semi-automatic manner.

In the accompanying drawings Figure 1 15 is a plan, somewhat diagrammatical, representing a structure embodying the invention; and Fig. 2 is an elevation showing a portion of the structure on an enlarged scale, on a section made at the line 2—2 of Fig. 1.

The drawings represent an embodiment 20 of the invention as it may be arranged in a single room, although it will be obvious that many variations of arrangement may be made according to the dictates of convenience or other motives, without departing 25 from the scope of the invention. The room has three portions marked respectively A, B and S. The portion A is an apartment easily accessible from the entrance 10 and is separated from the portion B by a railing 9 or other suitable means. It comprises a vestibule or area of suitable 30 size from which a passage or way 11 leads to the portion B. The latter is an apartment having tables and chairs 8 or other suitable accommodations of that nature. From apartment B a convenient exit is provided as at 12. When in use patrons enter 35 and proceed through the passage 11 to the portion B, and thence depart at will. The width of the passage 11 may conveniently be sufficient to hold a double file of patrons. Normally, the passage is occupied by a 40 single file, and the additional width enables any individual to pass others ahead of him 45 at will; but no individual can pass from the entrance to the portion B without going to the end 13 of the passage. At this is a station 14 for an inspector, hereinafter 50 more fully described.

Ranged along the side of the passage 11 is a series of stations or depots 15, 16, 17, 18, 19, 20, where supplies of food may be maintained for service to the patrons. Running 55 along the side of the passage, between these

stations and the place or way occupied by the single file of patrons, is a continuous shelf 21 of suitable height and width to support a succession of trays traveling thereon which, when the structure is in use, are 60 guided and controlled by the hands of the individual patrons and are pushed by them along this shelf as on a track from station to station at will.

The shelf preferably has a flat top as illustrated, and is wide enough so that a tray resting thereon can be left momentarily unattended. The free space beside this shelf or track, as illustrated, enables a tray resting thereon whether stationarily or in motion, to project somewhat over the service stations, in position for neat service by ladle or otherwise from said stations to the tray. The flatness and horizontality of the top of the shelf, coupled with the flatness of the 75 underside of the tray causes those portions of the trays that overhang the service stations to pass at uniform elevation above them and in a level position, so that dishes thereon are in level position for receiving 80 and holding service of liquids, and are prevented from sliding about on the tray.

The station 15, nearest the entrance, is preferably a place where a supply of trays is kept. A pile of these marked 15' is represented in the drawing. Each patron upon reaching this station receives one tray from the supply, to which may be added a napkin, with fork and other implements. A menu or list 22 of food ready for service 90 may be arranged upon the wall adjacent in such manner as to be visible to patrons while approaching this point and passing beyond. The succeeding stations marked 16 to 20 inclusive are for service of different 95 varieties of food. They preferably are arranged upon one or more tables adjacent to the shelf 21 upon which the trays travel, so that the shelf and the trays thereon intervene between the patron and the respective 100 stations.

The stations for service of food are preferably arranged with a carving station for various meats at or near the head, as at station 16. Subject to that variation, the 105 arrangement of stations follows the ordinary order of service of food at a meal, viz., meat and fish at the first station 16, roast, boiled or otherwise prepared; at the next station 17 soups and vegetables; and at suc- 110

ceeding stations 18, 19 and 20, in order, incidental items such as bread and butter; then beverages, then desserts. Obviously, any desired different arrangement may be used. As a patron passes the various stations his tray receives from each whatever portion of food he selects. Upon leaving the passage his tray passes within view of the inspector at station 14 and there receives from the inspector a check or memorandum denoting the total price of what it contains. The patron then enters the space B where are tables and seats.

The above described structures interpose no obstacle to prevent any patron from going as rapidly as he desires from the entrance through the passage 11 into the place B; and any patron in line may leave the file at any station and go immediately to the end 13 of the passage and into place B, passing those ahead of him, it being understood that in such case he removes his tray from the shelf and carries it in hand.

At the station 16 attendants may be provided to carve for the patron such meats as he signifies. If preferred, attendants may also stand in space S at each later station, to place upon each tray as it passes such things as the person controlling it shall indicate. If a patron wishes anything additional after entering space B, he may return past the station 13 into passage 11 and supply himself at the proper station, and then upon reentering space B a suitable check indicating a corrected total charge is given him by the inspector, in exchange for that previously given. Upon finishing, the patron leaves his tray where he has been sitting and departs through exit 12, where he pays the amount designated by his check at a cashier's station 23. An attendant removes the tray.

I claim as my invention:

1. A serving device comprising a track having an unobstructed upper surface, com-

bined with a multiplicity of removable carrier trays adapted to fit thereon and to move thereon along the track, the top of the track coöperating with the under sides of the trays to hold the trays horizontal in the transverse direction; a multiplicity of depots arranged in sequence alongside the track, the depots being severally adapted for holding and for service of different classes of foods; and a way alongside the track, on the other side thereof from said sequence of depots, for persons to walk alongside while propelling trays along the track.

2. A serving device comprising a stationary flat-topped track, combined with a multiplicity of food service stations arranged in sequence along and below the track on one side thereof; a way for persons to walk along the track on its other side; and a multiplicity of removable carrier trays with flat bottoms wider than the track and adapted to project out laterally therefrom over parts of the service stations while resting on the track, the track being adapted to maintain said trays horizontal when so projecting.

3. A serving device comprising a track having an unobstructed upper surface combined with a multiplicity of food service stations arranged in sequence alongside the track, on one side thereof, and a way for persons to walk alongside the track on the other side thereof, the said track being adapted to stabilize in substantial horizontally flat bottomed trays resting movably thereon while receiving food from said stations and transporting it along the track under propulsion of persons walking in said way.

Signed by me at Boston, this 28th day of May, 1909.

ALBERT M. WESTON.
